US00D494969S1

(12) **United States Design Patent** (10) Patent No.: **US D494,969 S**
Lin (45) Date of Patent: **** Aug. 24, 2004**

(54) **USB FLASH MEMORY DRIVE**

(75) Inventor: **Chia-Chuan Lin**, Taipei (TW)

(73) Assignee: **BENQ Corporation**, Taoyuan (TW)

(**) Term: **14 Years**

(21) Appl. No.: **29/188,021**

(22) Filed: **Aug. 11, 2003**

(51) LOC (7) Cl. **14-02**

(52) U.S. Cl. **D14/356**

(58) Field of Search **D14/356, 433,
D14/434; 710/62, 74; 361/684**

(57) **CLAIM**

The ornamental design for an USB flash memory drive, as shown and described.

DESCRIPTION

FIG. 1 is a perspective view thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plane view thereof;

FIG. 7 is a bottom plane view thereof; and,

FIG. 8 is a perspective view in use state thereof.
